UNITED STATES PATENT OFFICE.

HOWARD A. THOMPSON, OF EDGEWOOD BOROUGH, PENNSYLVANIA, ASSIGNEE TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 25, 1927. Serial No. 201,302.

My invention relates to railway traffic controlling apparatus and particularly to apparatus of the type comprising train carried governing means controlled by energy received from the trackway. More particularly my present invention relates to the trackway portion of such apparatus.

I will describe two forms of trackway apparatus embodying my invention, and will then point out the novel features thereof in claims.

In the accompanying drawings, Fig. 1 is a diagrammatic view illustrating one form of trackway apparatus embodying my invention. Fig. 2 is a diagrammatic view showing a modified form of the apparatus illustrated in Fig. 1 and also embodying my invention.

Similar reference characters refer to similar parts in both views.

Referring first to Fig. 1, the reference characters 1 and 1^a designate the track rails of a stretch of railway track over which traffic normally moves in both directions. These track rails are divided, by means of insulated joints 2, into a plurality of successive track sections, only one of which A—C is shown in the drawing. This section is further divided by means of insulated joints 2 to form two sub-sections A—B and B—C.

The stretch of track shown in the drawing is intended for use in a railway system using electric propulsion, and for this reason impedance bonds 3 of the usual and well known form are provided at each pair of insulated joints for the purpose of conducting propulsion current around such joints. The apparatus of my invention is equally well suited for use on a steam road, in which case the bonds 3 would, of course, be omitted.

Eastbound traffic through the stretch of track shown in the drawing is governed by two signals S¹ and S³ located adjacent points A and C, respectively, and westbound traffic through this stretch of track is governed by two other signals S² and S⁴ located at points C and A, respectively. The signals S may be of any suitable form and as here shown are of the semaphore type each

capable of displaying a proceed, a caution or a stop indication. The circuits for controlling the signals S form no part of my present invention and are omitted from the drawing for the sake of simplicity. For present purposes it is sufficient to state that signal S¹ normally indicates proceed but is arranged to indicate stop when an eastbound train occupies section A—C, the signal indicating caution when such train moves out of section A—C, and the signal indicating proceed when the train has moved out of the section to the right of point C. Furthermore, signal S⁴ indicates stop when a westbound train passes the first passing siding to the right of point C and remains at stop at least until such train has passed signal S¹. The operation of each of the remaining signals is similar to the operation of signal S¹ and will be understood without further explanation. Each of the signals S³ and S⁴ operates two circuit controllers designated by the reference characters V and W respectively with suitable distinguishing exponents and each arranged to be closed only when the corresponding signal indicates caution or proceed.

Associated with sub-section A—B is a track relay R^A having two windings 8 and 9, one of which, 8, is constantly connected across the rails adjacent the left-hand end of sub-section A—B. The remaining winding 9 of relay R^A is constantly supplied with alternating current of one frequency from a suitable source of energy such as an alternator 7 over line wires 4 and 4^a. In similar manner, sub-section B—C is provided with a track relay R^C having a winding 8 connected across the rails adjacent the right-hand end of the sub-section, and having also a second winding 9 constantly supplied with alternating current over line wires 4 and 4^a.

Associated with each of the track relays R is a repeater relay designated by the reference character P with an exponent corresponding to the location. The relays P are connected in series in a circuit which may be traced from line wire 4, through wires 12, 13 and 14, winding of relay P^A, wire 15, front contact 16 of relay R^A, wire 17, front contact 18 of relay R^C, wire 19,

winding of relay P^c , and wires 20 and 21 to line wire 4^a. It follows therefore that when relays R^A and R^c are both energized, relays P^A and P^c are also energized but that the 5 de-energization of either of the track relays R will result in the de-energization of both of the repeater relays P .

Alternating train controlling current, which in the present embodiment of my invention is of a different frequency from the current supplied to line wires 4 and 4^a, is 10 at times supplied to the rails of each subsection and is at times supplied to auxiliary conductors J one of which is provided in the 15 trackway adjacent each end of each track section. Referring particularly to the conductor J^A located adjacent the left-hand end of section A—C, this conductor is constantly connected with the secondary of a transformer F^A in series with the winding of a 20 checking relay G^A . The primary of transformer F^A is provided with a circuit which may be traced from a suitable source of energy such as an alternator 6 over line wire 25 5, wires 22, 28, and 29, primary of transformer F^A , wire 30, back contact 26 of relay P^A , wire 27, and line wire 5^a back to alternator 6. It follows that whenever the repeater relay P^A is de-energized, as by de-energization 30 of either of the relays R^A , R^c , alternating train controlling current is supplied to the primary of transformer F^A and that train controlling current is therefore supplied to the auxiliary conductor J^A and to relay G^A . 35 The supply of train controlling current to auxiliary conductor J^c adjacent the right-hand end of section A—C, and to the checking relay G^c is controlled by relay P^c in a manner similar to that just described in connection with the control of the supply of 40 current to relay J^A by relay P^A .

A second track relay Q^A has one winding 10 connected across the rails in parallel with relay R^A . A second winding 11 on relay Q^A 45 is at times supplied with alternating current of train controlling frequency over a circuit which may be traced from line wire 5, through wires 22 and 23, winding 11 of relay Q^A , wires 24 and 25, back contact 26 of relay P^A , and wire 27, to line wire 5^a. Winding 11 of relay Q^A is, therefore energized 50 only when relay P^A is de-energized, under which conditions the relay is responsive to alternating current of train controlling frequency present in the trackway. The control 55 of relay Q^c located adjacent point C is similar to the control of relay Q^A , and will be understood from the drawing without detailed explanation. The section to the left 60 of point A is provided with a line relay H^A and the section to the right of point C is provided with a line relay H^c , these line relays are controlled in accordance with the usual practice in absolute permissive block 65 signaling systems and since the control of

these relays forms no part of my present invention, I have omitted the control circuits from the drawing for the sake of simplicity. For the purpose of the present disclosure it is sufficient to state that both line relays H^A 70 and H^c are normally energized. When an eastbound train leaves the first passing siding to the left of section A—C, relay H^A , which governs westbound traffic, becomes de-energized and remains in this condition at 75 least until the train has passed point A. Similarly, when a westbound train leaves the first passing siding to the right of point C, relay H^c , which governs eastbound traffic, becomes de-energized and remains in this 80 condition at least until the train passes point C. Furthermore, relay H^A is de-energized when a westbound train occupies the first or second sections to the left of point A, and relay H^c is de-energized when an eastbound 85 train occupies the first or second sections to the right of point C.

The supply of train controlling current and of track circuit current to the rails adjacent the left-hand end of sub-section B—C is controlled by an auxiliary relay D^2 which is provided with a circuit from line wire 4, through wires 12 and 34, contact 35—36 of circuit controller W^4 , wire 38, front contact 39 of relay H^A , wire 40, front 90 contact 41 of relay R^A , wire 42, front contact 43 of relay G^A , wire 44, winding of relay D^2 , wire 45, back contact 46 of relay Q^c , wire 47, back contact 48 of relay R^c , and wires 49, 50 and 21, to line wire 4^a. It will be plain, 100 therefore, that relay D^2 is energized only when signal S^4 indicates caution or proceed, when relays H^A , R^A and G^A are energized and when relays Q^c and R^c are de-energized. A track transformer T^B_2 has its secondary 105 constantly connected with the rails adjacent the left-hand end of sub-section B—C. A train controlling transformer E^B_2 also has its secondary connected across the rails adjacent the left-hand end of sub-section B—C. 110 When relay D^2 is de-energized the primary of track transformer T^B_2 is connected over back contact 51 of relay D^2 with line wires 4 and 4^a, but when relay D^2 is energized, the primary of transformer E^B_2 is connected 115 over front contact 52 of relay D^2 with line wires 5 and 5^a. It follows therefore that the left-hand end of sub-section B—C is supplied with track circuit current or with train controlling current according as relay 120 D^2 is de-energized or energized, respectively.

A second auxiliary relay D^1 is provided with a circuit similar to the circuit already traced for auxiliary relay D^2 and serves to 125 select between transformers T^B_2 and E^B_2 , adjacent the right hand end of sub-section A—B in the same manner as relay D^2 selects between transformers T^B_2 and E^B_2 .

Train controlling current is at times sup- 130

plied to the left-hand end of sub-section A—B from transformer E^A , the secondary of which is constantly connected with the rails of the sub-section in parallel with winding 8 of track relay R^A and winding 10 of track relay Q^A . The primary of this transformer is provided with a circuit which may be traced from line wire 5, through wires 22, 28 and 53, primary of transformer E^A , wire 54, back contact 55 of relay R^A , wire 56, contact 35—36 of circuit controller V^A , front contact 57 of line relay H^A , wire 58, front contact 59 of relay G^A , wire 25, back contact 26 of relay P^A and wire 27 to line wire 5^a. A transformer E^C having its secondary connected across the rails adjacent the right-hand end of sub-section B—C is provided with a primary circuit similar to the circuit just traced for the primary of transformer E^A .

Before describing the operation of the apparatus as a whole, it should be pointed out that the trackway apparatus herein shown and described is suitable for co-operation with train carried governing means not shown in the drawing. In at least one form of train carried apparatus suitable for co-operation with the trackway circuits herein illustrated, the continuous supply of train controlling current to the rails from a point in advance of the train causes a proceed indication to be displayed on board the train. Should the supply of such train controlling current be interrupted an automatic application of the brakes would result unless the engineman should acknowledge the change in traffic conditions by taking some deliberate action. With a train provided with train carried governing means of the type described if the engineman has acknowledged a change in traffic conditions following the interruption of the train controlling current and the train then passes an auxiliary conductor J which is being supplied with train controlling current, the engineman is again forced to acknowledge when the train passes such conductor to prevent an automatic application of the brakes.

As shown in the drawing, the section A—C is unoccupied and signals S^1 , S^3 , S^2 and S^4 all indicate proceed. Relays H^A and H^C are both energized. Relays D^1 and D^2 are both reenergized so that track circuit current is supplied to the right-hand end of sub-section A—B and to the left-hand end of sub-section B—C. Relays R^A and R^C are therefore energized and relays P^A and P^C are also energized. The primary circuit for transformers F^A and F^C are open at back contacts 26 of relays P^A and P^C , respectively, and no train controlling current is being supplied to the auxiliary conductors J^A and J^C . The circuits for train controlling transformers E^B_1 and E^B_2 are open at front contacts 52 of relays D^1 and D^2 , respectively and the primary circuit of transformer E^A is open at back contact 55 of track relay R^A , and front contact 59 of relay G^A . In similar manner the primary circuit for transformer E^C is also open. Under these conditions no train controlling current is supplied to the rails of any portion of section A—C, and relays Q^A and Q^C are both de-energized. Furthermore, the circuit for winding 11 of each of the relays Q is open at back contact 26 of the associated repeater relay P . I will now assume that a west-bound train moves through the stretch of track shown in the drawing. When this train left the passing siding to the right of point C, signals S^1 and S^3 moved to the stop position and relay H^C became de-energized. When the train enters sub-section B—C, relay R^C opens, thereby de-energizing repeater relays P^A and P^C . The closing of back contact 26 of relay P^C supplies train controlling current to transformer F^C and hence to relay G^C and auxiliary conductor J^C , and the closing of back contact 26 of relay P^A supplies train controlling current to transformer F^A and hence to auxiliary conductor J^A and relay G^A . Transformer E^C is de-energized under these conditions because its primary circuit is open at front contact 57 of relay H^C and also at circuit controller V^3 . With relay R^C de-energized and with relay G^A energized, relay D^2 becomes energized, thereby interrupting the supply of track circuit current to transformer T^B_2 and supplying train controlling current to the rails of sub-section B—C through transformer E^B_2 . The train therefore receives a proceed indication as it proceeds through sub-section B—C. I will now assume that this train backs out of sub-section B—C or leaves the sub-section by a siding not shown in the drawing before any portion of the train enters sub-section A—B. Train controlling current supplied by transformer E^B_2 now flows through winding 10 of relay Q^C . But winding 11 of this relay is supplied with alternating current of train controlling frequency over a circuit including back contact 26 of relay P^C and relay Q^C , therefore becomes energized. The opening of back contact 46 of relay Q^C then de-energizes relay D^2 , interrupting the supply of train controlling current to sub-section B—C and restoring the supply of track circuit current to this sub-section B—C from transformer T^B_2 . Relay Q^C therefore becomes de-energized and relay R^C picks up. The opening of back contact 26 of relay P^C interrupts the primary circuit of transformer F^C and allows relay G^C to open thereby restoring the apparatus to its original condition.

If, however, the westbound train moves from sub-section B—C into sub-section A—B, relay R^A becomes de-energized, there-

by closing at back contact 55 thereon, the primary circuit for transformer E^A . Train controlling current is, therefore supplied to the rails adjacent the left-hand end of sub-section A—B, but it should be noticed that the polarity of the current supplied to the primary 10 under these conditions is of the opposite polarity supplied to this winding by transformer E^B , and the relay is, therefore held in its de-energized position. The train, therefore proceeds through the section under a proceed indication. The de-energization of relay R^A interrupted the circuit for relay D^2 which is now open to supply track circuit current to the rails of sub-section B—C. When the train leaves sub-section B—C, therefore, the current supplied to relay R^C energizes relay R^C and restores the apparatus to its normal condition.

When the train moves out of sub-section A—B, track circuit current from transformer T^B , energizes relay R^A . Relay R^C is already energized so that relays P^A and P^C pick up, and restore the apparatus to the condition corresponding to an unoccupied section.

I will next assume that a westbound train occupies the section to the left of point A, and that a following train enters section A—C. Under these conditions, circuit controllers V^4 and W^4 and relay H^A will be de-energized so that the relay D^2 does not pick up when the following train enters sub-section B—C. No train controlling current is supplied to the rails of the sub-section from a point in advance of a following train and the engineman of this following train must therefore acknowledge to prevent an automatic application of the brakes.

When the following train enters sub-section A—B, relay R^A becomes de-energized as before, but the primary circuit of transformer E^A is open at circuit controller V^4 and front contact 57 of relay H^A , so that no train controlling current is supplied to the rails at the left-hand end of sub-section A—B. Conductor J^A is energized, however, so that when the train passes this conductor the engineman must again acknowledge to prevent an automatic application of the brakes. It should be pointed out that should any defect occur in the auxiliary conductor J^A , relay G^A could not be energized. The circuit for relay D^2 is carried over a front contact 55 of relay G^A and it follows that if any fault should occur in the circuits by means of which train controlling current is supplied to the auxiliary conductor J^A , relay D^2 could not be energized. The apparatus therefore insures that the circuits for conductors J^A are intact if relay D^2 becomes energized to supply train controlling current to sub-section B—C.

If an eastbound train is located between point A and the first passing siding, to the

left of this point, relay H^A will be de-energized and circuit controller V^A will be open. Under these conditions, no train controlling current can be supplied to the rails of section A—C and the engineman must acknowledge as he passes the auxiliary conductor J^A to prevent an automatic application of the brakes.

The operation of the apparatus for east-bound trains is similar in all respects to the operation just described in connection with westbound trains and it will be understood from the drawing without further explanation.

In certain types of train controlling systems the trackway is at times supplied with alternating train controlling current which is periodically varied at different frequencies in accordance with traffic conditions and the train carried governing means is selectively responsive to the frequency of such variations. The apparatus illustrated in Fig. 2 is suitable for controlling the trackway apparatus in a system of this type. Referring to this view, the section A—C is divided as before into two sub-sections A—B and B—C. The signals S^1 , S^2 , S^3 and S^4 and the line relays H^A and H^C are controlled in the same manner as in Fig. 1. The track relays R^A and R^C , responsive to track circuit current, are connected across the left-hand end of sub-section A—B and right-hand end of sub-section B—C in a manner similar to the connection of the corresponding parts in Fig. 1. Associated with line relay H^A is a stick relay K^A which is normally de-energized but is arranged to be energized when any portion of a west-bound train occupies the section to the left of point A. In similar manner a normally de-energized stick relay K^C associated with line relay H^C is arranged to be energized when any portion of an east-bound train occupies the section to the right of point C. The circuits for controlling the stick relays K^A and K^C are the same as are customarily used in absolute permissive block signaling systems and since they form no part of the present invention I have omitted them from the drawing for the sake of simplicity. In addition to the auxiliary relays D^1 and D^2 located adjacent point B two other auxiliary relays L^1 and L^2 are provided.

For controlling the supply of train controlling current to the trackway, a code transmitting device is provided adjacent the junction of each two adjacent sub-sections. Referring particularly to the device X^B , this device comprises a motor 92 which is at times supplied with energy from line wires 5 and 5^a. This motor drives a code wheel 93 which operates a contact finger 95 to move the finger alternately into engagement with two fixed contacts 95^a and 95^b. The code wheel 93 also operates a contact 130

finger 96 which is moved alternately into engagement with fixed contacts 96^a and 96^b when the code wheel is operated. A second code wheel 94 operates two movable fingers 97 and 98 each of which co-operates with two fixed contacts. It will be seen that the code wheels 93 and 94 have different numbers of teeth on their periphery so that when the motor 92 is operated the contact fingers 95 and 96 operated by code wheel 93 are driven at one speed and the contact fingers 97 and 98 operated by code wheel 94 are driven at a different speed.

Relay D² adjacent point B is provided with a circuit which may be traced from line wire 4^a, through wires 60 and 61, back contact 62 of relay R^c, wires 63 and 64, winding of relay D², wire 65, contact 35-36 of circuit controller W⁴, wire 66, front contact 67 of line relay H^A, wire 68, front contact 69 of relay R^A, and wires 70 and 71 to line wire 4. This circuit is provided with a branch which passes from wire 63, through wire 72, winding of relay L², wire 73, front contact 74 of relay K^A, wire 75, back contact 67 of relay H^A, wire 68, front contact 69 of relay R^A, and wires 70 and 71 to line wire 4. It follows that when relay R^c is de-energized and when relay R^A is energized, relay D² is energized if signal S⁴ indicates caution or proceed and line relay H^A is energized, but if line relay H^A is de-energized, relay L² is energized if relay K^A is picked up. The circuits for relays D¹ and L¹ are similar to those just described for relays D² and L² and will be understood from the drawing without tracing them in detail.

The motor 92 of coding device X^B is normally de-energized but when relay D² becomes energized this motor is connected across wires 5 and 5^a through front contact 101 of relay D². If relay L² is energized, current is supplied to motor 92 over front contact 102 of this relay. In similar manner the motor 92 is provided with two other circuits, one including front contact 103 of relay D¹ and the other including front contact 104 of relay L¹. It follows that the motor 92 of device X^B is energized when any one of relays D¹, D², L¹ or L² is energized. Track circuit current and train controlling current are at times supplied to sub-section B-C through the single transformer T^B₂. When relays D² and L² are both de-energized, the circuit for transformer T^B₂ passes from line wire 4, through wires 105 and 106, back contact 107 of relay L², wire 108, back contact 109 of relay D², wire 110, primary of transformer T^B₂, and wires 111 and 112 to line wire 4^a. Under these conditions uninterrupted track circuit current is supplied to the rails adjacent the left-hand end of sub-section B-C. If relay D² becomes energized, however, the closing of front contact 101, energizes the motor 92 of device

X^B. Contact finger 97 therefore swings alternately into engagement with contacts 97^a and 97^b. Each time contact 97-97^a is closed, current flows from line wire 5, through wires 118, 119, 120 and 121, front contact 122 of relay D², wire 123, contact 97-97^a, wire 115, front contact 109 of relay D², wire 110, primary of transformer T^B₂, and wires 111, 124 and 125 to line wire 5^a. Under these conditions, therefore, alternating train controlling current is supplied to the rails of sub-section B-C. This circuit is closed, however, only when contact 97-97^a is closed and when contact 97-97^b is closed, current flows from line wire 4, through wires 105, 113 and 114, contact 97-97^b, wire 115, front contact 109 of relay D², wire 110, primary of transformer T^B₂, and wires 111 and 112 to line wire 4^a. When relay D² is energized, therefore, current is supplied to sub-section B-C in the form of alternate impulses of track circuit current and train controlling current. Current supplied to the trackway in the manner just described I will hereinafter term the proceed code. When relay D² is de-energized and relay L² is energized motor 92 is operated by current supplied thereto over front contact 102 of relay L². Under these conditions an impulse of train controlling current is supplied to the primary of transformer T^B₂ each time contact 95-95^a is closed, over a circuit which may be traced from line wire 5, through wires 118, 119 and 126, front contact 127 of relay L², wire 128, contact 95-95^a, wire 117, front contact 107 of relay L², wire 108, back contact 109 of relay D², wire 110, primary winding of transformer T^B₂, and wires 111, 124 and 125, to line wire 5^a. When the contact finger 95 swings in the other direction, current flows from line wire 4, through wires 105, 113, and 116, contact 95-95^b, wire 117, front contact 107 of relay L², wire 108, back contact 109 of relay D², wire 110, primary of transformer T^B₂, and wires 111 and 112, to line wire 4^a. Under these conditions current is supplied to the rails of sub-section B-C in the form of alternate impulses of train controlling current and track circuit current, but the frequency of these impulses is different from the frequency of the impulses corresponding to the proceed code and I will therefore term the current supplied to the trackway under the conditions thus described the "caution" code. The relays D¹ and L¹ control the supply of current to sub-section A-B through the transformer T^B₂ in a manner similar to that just described in connection with the control of the supply of current to sub-section B-C by relays D² and L².

Train controlling current is at times supplied to the rails adjacent the left-hand end of sub-section A-B through transformer E^A, the primary of which is provided with

two circuits. The circuit for the proceed code may be traced from line wire 5, through wire 76, back contact 77 of relay R^A , wires 99 and 79, contact 98-98^b of device X^A , wire 80, contact 35-36 of circuit controller V^4 , wire 81, front contact 82 of relay H^A , wire 83, back contact 84 of relay R^A , wire 85, primary of transformer E^A , and wires 86 and 87 to line wire 5^a. The motor 92 of device X^A is supplied with energy over back contact 77 of relay R^A and it follows that when relay R^A is de-energized, section A-B is supplied with the proceed code if relay H^A is energized and signal S^4 indicates caution or proceed. Transformer E^A is provided with another circuit which may be traced from line wire 5, through wire 76, back contact 77 of relay R^A , wires 99 and 79, contact 96-96^b, wire 88, front contact 89 of relay K^A , wires 90 and 91, back contact 82 of relay H^A , wire 83, back contact 84 of relay R^A , wire 85, primary of transformer E^A , and wires 86 and 87 back to line wire 5^a. The circuit just traced is provided with a branch which passes from wire 90, through wire 100, and contact 35-37 of circuit controller V^4 closed when signal S^4 is in its stop position wire 81, and front contact 82 back to wire 83. It follows, therefore, that if relay R^4 is de-energized no train controlling current is supplied to the rails of sub-section A-B if relay K^A is de-energized. If, however, relay K^A closed, the caution code is supplied to sub-section A-B if signal S^4 indicates stop or if line relay H^A is de-energized. The circuits for transformer E^C are similar to those just described for transformer E^A and will be apparent from the drawing.

As shown in the drawing the relays H^A and H^C are both energized and all of the signals S indicate proceed. Relays K^A and K^C are both de-energized and the section A-C is unoccupied. Relays R^A and R^C are energized, relays D^1 , D^2 , L^1 and L^2 all de-energized so that the code devices X are all de-energized and track circuit current is supplied without interruption to the right-hand end of sub-section A-B and to the left-hand end of sub-section B-C. I will now assume that a westbound train moves through the stretch of track shown in the drawing. When this train enters sub-section B-C relay R^C becomes de-energized, thereby closing, at contact 62 thereon, the circuit for relay D^2 , which thereupon becomes energized. The motor 92 of device X^B is, therefore, energized and the proceed code is supplied to the left-hand end of sub-section B-C, so that the train is supplied with the proceed code as it proceeds through sub-section B-C. I will now assume that the train backs out of sub-section B-C or leaves the section by a siding not shown in the drawing. The next impulse of track cir-

cuit current supplied to the rails of the sub-section will energize relay R^C , thereby opening back contact 62 and de-energizing relay D^2 to restore the apparatus to its original condition. If the westbound train continues into sub-section A-B, the de-energization of relay R^A energizes motor 92 of code device X^A and completes the circuit over which proceed code is supplied to the primary of transformer E^A . The train, therefore, receives a proceed indication as it proceeds through the sub-section A-B. After the rear of the train has passed out of sub-section B-C, the next impulse of track circuit current supplied to relay R^C energizes this relay as before to restore the apparatus associated with sub-section B-C to its normal condition. In similar manner when the train passes out of sub-section A-B, the relay R^A becomes energized by track circuit current supplied thereto by transformer T^B , thereby interrupting the circuit for motor 92 of relay X^A which includes back contact 77 of relay R^A .

I will now assume that a westbound train occupies the section to the left of point A, and that a second westbound train moves through the stretch of track shown in the drawing. When this second train enters sub-section B-C relay R^C opens as before but relay H^A is now de-energized, signal S^4 is at stop, and relay K^A is energized. As a result, relay L^2 picks up, thereby supplying current to transformer T^B in accordance with the caution code. In similar manner when the train enters sub-section A-B, the de-energization of relay R^A operates to supply caution code to transformer E^A . I will now assume that an eastbound train is located between the point A and the first siding to the left of this point. Relay H^A is, therefore de-energized but relay K^A is also de-energized so that should a westbound train enter sub-section B-C under these conditions, relays D^2 and L^2 would both remain de-energized and no train controlling current would be supplied to the rails of section B-C. In similar manner should this westbound train enter sub-section A-B the train controlling circuits for transformer E^A would remain open so that no train controlling current would be supplied to sub-section A-B.

Furthermore, should sub-section A-B be occupied by a train, relay R^A would be de-energized and if a westbound train entered sub-section A-B under these conditions, relays D^2 and L^2 would both remain de-energized and no train controlling current would be supplied to such westbound train.

The operation of the apparatus for eastbound movements is exactly the same as has been described in connection with westbound movements and will be understood from the drawing without further explanation.

Although I have herein shown and de-

scribed only two forms of trackway apparatus embodying my invention, it is understood that various changes and modifications may be made therein within the scope of the appended claims without departing from the spirit and scope of my invention.

Having thus described my invention what I claim is:

1. In combination, a section of railway track having a right and a left sub-section over which traffic moves in both directions, a first relay, means for supplying track circuit current to the right hand end of said left sub-section when such relay is de-energized, means for supplying train controlling current to the right hand end of the left sub-section when such relay is energized, a second relay, means for supplying track circuit current to the left hand end of the right sub-section when the second relay is de-energized, means for supplying train controlling current to the left hand end of the right sub-section when the second relay is energized, means effective when a train moving toward the right occupies the left sub-section to energize said first relay, means for supplying train controlling current to the right hand end of the right sub-section, means effective when a train moving in the opposite direction occupies the right sub-section to energize said second relay, and means for supplying train controlling current to the left hand end of the left sub-section when such train occupies the left sub-section.
2. In combination, a stretch of railway track, a first relay, means effective when the first relay is de-energized to supply track circuit current to the rails of the section, means effective when the first relay is energized to supply train controlling current to the rails of the stretch, a second relay responsive to such track circuit current but not to train controlling current and connected with the rails of the stretch, a third relay connected with the rails of the stretch and responsive to train controlling current but not to track circuit current, and a circuit for the first relay including a back contact of the second relay and a back contact of the third relay.

3. In combination, a section of railway track comprising a forward and a rear sub-section, a first relay, means effective when the first relay is energized to supply train controlling current to the rear sub-section, an auxiliary trackway conductor associated with the forward sub-section, a second relay, means effective when a train occupies either sub-section to supply current to the second relay and the auxiliary conductor in series, means controlled by traffic conditions in advance of the forward sub-section for supplying train controlling current to the rails of the forward sub-section when such sub-section is occupied, and a circuit for the first

relay including a front contact of the second relay and controlled by traffic conditions in advance of the rear sub-section.

4. In combination, a section of railway track, an auxiliary conductor associated with the section, a first relay, means effective when the section is occupied to supply train controlling current to the first relay in series with the auxiliary conductor, means controlled by traffic conditions in advance and effective when the first relay is energized to supply train controlling current to a portion of the section, a second relay, a circuit for said second relay including a front contact of the first relay and controlled by traffic conditions, and means controlled by the second relay for supplying train controlling current to a different portion of the section.

5. In combination, a section of railway track, means for normally supplying track circuit current to the rails adjacent one end of the section, a first track relay connected with the rails adjacent the other end of the section and responsive to such track circuit current, means controlled by said first track relay and controlled by traffic conditions for at times interrupting such supply of track circuit current and for supplying train controlling current to the rails adjacent said one end of the section, a second track relay connected with the rails adjacent said other end of the section and responsive to said train controlling current and arranged when energized to restore the supply of track circuit current to the rails adjacent the said one end of the section.

6. In combination, a section of railway track comprising a forward and a rear sub-section, an auxiliary conductor for the forward sub-section, a first relay, means for at times supplying train controlling current to the first relay and the auxiliary conductor in series, and a second relay controlled by the first relay for governing the supply of train controlling current to the rear sub-section.

7. In combination, a forward and a rear sub-section, means for normally supplying track circuit current to the forward section, a track relay for said forward section responsive to such track circuit current, a second relay controlled by said track relay and by traffic conditions in advance of the forward sub-section, and means effective when such second relay is energized to supply train controlling current to the rear sub-section but effective when such second relay is deenergized to supply track circuit current to the rear sub-section.

8. In combination, a section of railway track, an auxiliary relay, means effective when the auxiliary relay is de-energized to supply track circuit current of one frequency to the rails of the section, means effective when the auxiliary relay is energized to supply train controlling current of a different

frequency to the rails of the section, a first track relay connected with the rails and responsive to track circuit current but not to train controlling current, a second track relay having two windings one connected with the rail of the section, means operating when the first track relay is de-energized to sup-

ply current of train control frequency to the second winding of the second track relay, and a circuit for the auxiliary relay including back contacts of the first and second track relays. 10

In testimony whereof I affix my signature.
HOWARD A. THOMPSON.
